UNITED STATES PATENT OFFICE.

GEORGE S. DE BURGER AND JOHN E. BAYLESS, OF INDIANAPOLIS, INDIANA.

DRAWBAR DRAFT GEAR.

Application filed March 8, 1924. Serial No. 697,842.

To all whom it may concern:

Be it known that we, GEORGE S. DE BURGER and JOHN E. BAYLESS, citizens of the United States, residing at Indianapolis, in the county of Marion and the State of Indiana, have invented a new and useful Draw-Bar Draft Gear, of which the following is a specification.

Our invention relates to an improvement in a draw bar draft gear for freight and passengers cars, trucks and the like, and the objects of our invention are to obtain means whereby the gear may readily be assembled or disassembled without shop equipment in case of draw bar breakage at points remote from shop assistance, an increased cushion in starting and stopping as compared to the customary gear, and positive driving contact following a predetermined take-up in the draft spring.

We attain these and other objects as may become apparent in the following description by the means as shown in the accompanying drawing, in which—

Fig. 1 is a side elevation of an end of a freight car showing our draft gear in dotted lines assembled within the end of the customary center sill of the car; Fig. 2, a side elevation of the draft gear with one of the side channel members of the car sill removed; Fig. 3, a top plan view of the draft gear; Fig. 4, a vertical section taken on the line 4—4 of Fig. 2.

Like characters of reference indicate like parts throughout the several views.

The usual and customary construction of freight cars embodies a center sill 5 built up of two channel members 6 and 7 with the legs turned inwardly, and we have adapted our draft gear such that it may, if desired, be incorporated within the sill 5 using the members 6 and 7 as sides of this gear. However, in cars not employing a center sill, we use two side members, similar to the channel members 6 and 7 of the proper length, and secure these side members to the under timbers or sills of the car in the place of the customary draft gear.

Referring to Fig. 1, the draw bar 8 is an integral casting with the usual square shank 9 and coupling head 10 supported in the usual hanger 11. Between the side members 6 and 7 and securely riveted to them by the angles 12 and 13 is the front stationary block 14 centrally through which passes the

draw bar 8. A pair of lugs 15 and 16 is formed on the bar 8 back of the block 14 and a short distance back of lugs 15 and 16 is formed a second pair of lugs 17 and 18, both pairs lying in the same horizontal plane. A driving shoulder 19, securely riveted to the side member 6 projects between the lugs 15 and 17, and a similar shoulder 20, securely riveted to the other side member 7, projects between the lugs 16 and 18. Slidely mounted on the bar 8 are two follow blocks 21 and 22 having their ends fitted in the channel members 6 and 7 and adapted to slide thereon.

The follow blocks 21 and 22 are spaced and held apart by the compression spring 23. Normally, the spring 23 acts only as a spacer and holds the blocks 21 and 22 in loose contact against the stops 24, 25 and 26, 27. A tapered key 28 is put through the bar 8 immediately back of the follow block 22 such that the bar 8 is so retained that the lugs 17 and 18 contact the block 21 from the front side and the key 28 contacts the back side of block 22.

A third follow block 29 contacts the end of the bar 8 and is there loosely held by the compression spring 30 which is held in position by the post 31 carried by the back stationary block 32 against which the spring 30 bears. The block 32 is securely riveted to the side members 6 and 7 by angles 33 and 34. The bar 8 passes through the block 14, 21 and 22 with considerable play such that the bar 8 may have ample freedom to provide for displacement of the bar 8 as the car passes around curves, over grades, and inequalities in the track.

Should the head 10 become inoperative or the bar 8 pull in two, and a new bar be required, the bar 8 is revolved in the blocks until the key 28 is turned such that it may be withdrawn. Normally the bar 8 is carried such that the large end of the key is upward. The bar 8 is then turned, as indicated in Fig. 4, such that the lugs 15, 16 and 17, 18 may pass through the slots 35 and 36 provided in the block 14 as the bar 8 is pulled out. By so turning the bar, the lugs 17 and 18 also are turned to clear and pass shoulders 19 and 20. As the bar 8 is further withdrawn, the spring 23 drops out, and if desired, either or both of the follow blocks 21 and 22 may be turned toward either side member 6 or 7 and taken out.

Also, if desired, as the bar 8 is out of the way, the compression spring 30 may be taken out by sliding or turning the follow block 29 ahead out of the way, after which the block 29 may be so turned as to be withdrawn from between the side members 6 and 7.

To describe the manner of operation, suppose the train of cars to be starting ahead such that the pull on the bar 8 is forward.

10 As the pull starts on the bar 8, the entire load at the beginning of the pull is on the key 28 bearing against the block 22 which pull exerts a compressive action on the spring 23, such compressive action being entirely borne by the block 21 and in turn against the stops 24 and 25, through which the pull is transmitted to the side members 6 and 7 of the sill 5. As the pull on the bar 8 is increased, the spring 23 is further compressed such that the lugs 15 and 16 contact the front stationary block 14 and simultaneously the lugs 17 and 18 contact the shoulders 19 and 20, in which position the load or pull on the bar 8 is not only transmitted through the spring 23 to the side members 6 and 7 but also positively through the block 14 and shoulders 19 and 20 to the side members 6 and 7. Normally, however, as the train gets under way, the tension of the spring 23 is sufficient to take the steady pull forward and the lugs do not contact the front block of the shoulders.

25

30

35

In backing the car, or should the coupling head receive an impact such as in coupling two cars together, the bar 8 is pushed backward, which action causes the lugs 17 and 18 to press the block 21 against the spring 23 to compress it against the block 22 held from further backward motion by the stops 26 and 27 so that in this manner part of the load is transmitted to the side members 6 and 7 of the sill 5. At the same time the foregoing action occurs, the end of the bar 8 presses the block 29 back to compress the spring 30 against the stationary block 32 such that the remainder of the backward load is transmitted accordingly to the members 6 and 7. Should this backward push be sufficiently great, as in unduly violent impacts, or in starting the car, the lugs 15 and 16 will contact with the shoulders 19 and 20, and also the end of the draw bar 8 will contact the post 31, but only after the travel of the bar 8 has been greatly arrested through the predetermined compression of the springs 23 and 30. While we have here shown single springs, either or both springs 23 and 30 may be multiple springs as may be required by varying specifications for predetermined travel under prescribed loads or impacts, and while we have here shown one construction of our invention in the form now best known to us as applied to a freight car, we desire to set out that the same construction or varia-

tions of the same construction may be applied to other vehicles requiring a draw bar without departing from the spirit of the invention, and we therefore do not desire to be limited to the precise construction as shown, nor any more than be required by the following claims.

We claim:

1. In a draw bar draft gear, supporting members, an integral draw bar between the supporting members, shoulders on the supporting members, driving lugs extending from the draw bar and adapted to contact said shoulders by appreciable travel of said draw bar, a guiding member rigidly carried by said supporting members slidably carrying said draw bar and preventing the forward withdrawal of the draw bar by reason of the lugs projecting therefrom, said guiding member having slots therein to permit passage of the lugs therethrough upon axial rotation of the draw bar, and means of preventing rotation of the draw bar.

2. In a draw bar draft gear, supporting members, a guiding member, an integral draw bar carried by the supporting members and slidably passing through said guiding member, shoulders on said supporting members, driving lugs on said draw bar adapted to contact said shoulders and said guiding member upon appreciable travel of the draw bar, said guiding member having slots therethrough located so as to permit passage of the lugs on the draw bar after rotating the draw bar from its normal position, follow members slidably carried on the draw bar, a spring normally holding said follow blocks apart, follow block stops on the supporting members, and a tapered key vertically passing through the draw bar from above, the travel of said follow blocks on the draw bar being limited by said lugs and said key.

3. In a draw bar draft gear, supporting members, a guiding member, an integral draw bar carried by the supporting members and slidably passing through said guiding member, shoulders on said supporting members, driving lugs on said draw bar adapted to contact said shoulders and said guiding member upon appreciable travel of the draw bar, said guiding member having slots therethrough located so as to permit passage of the lugs on the draw bar after rotating the draw bar from its normal position, follow members slidably carried on the draw bar, a spring normally holding said follow blocks apart, follow block stops on the supporting members, and a tapered key vertically passing through the draw bar from above, the travel of said follow blocks on the draw bar being limited by said lugs and said key, a rear bumper block, a rear follow block contacting the end of said draw bar, and a bumper spring nor-

mally spacing said rear follow block apart from the bumper block.

4. In a draw bar draft gear, supporting members, a guiding member, an integral draw bar carried by the supporting members and slidingly passing through said guiding member, shoulders on said supporting members, driving lugs on said draw bar adapted to contact said shoulders and said guiding member upon appreciable travel of the draw bar, said guiding member having slots therethrough located so as to permit passage of the lugs on the draw bar after rotating the draw bar from its normal position, follow members slidingly carried on the draw bar, a spring normally holding said follow blocks apart, follow block stops on the supporting members, and a tapered key vertically passing through the draw bar from above, the travel of said follow blocks on the draw bar being limited by said lugs and said key, a rear bumper block, a rear follow block contacting the end of said draw bar, and a bumper spring normally spacing said rear follow block apart from the bumper block, and means for rigidly

stopping the backward travel of the draw bar.

5. In a draw bar draft gear, supporting members, shoulders extending from the supporting members, an integral draw bar between the supporting members, a front stationary member having a hole therethrough to slidingly receive the draw bar and having lug slots extending upwardly and downwardly from the hole in a vertical plane, lugs extending horizontally from each side of the draw bar and adapted to contact said shoulders and said front stationary block upon appreciable travel of said draw bar, a key passing through the draw bar, follow blocks slidingly carried on the draw bar, a spring normally spacing the follow blocks apart against the lugs and the key, and stops on the supporting members limiting the travel of the follow blocks.

Signed this 5th day of March, 1924, at Indianapolis, in the county of Marion, and State of Indiana.

GEORGE S. DE BURGER.
JOHN E. BAYLESS.
